UNITED STATES PATENT OFFICE.

HERMAN H. DEUTSCHER, OF CARROLLTON, MISSOURI.

FARM-GATE.

1,102,481.

Specification of Letters Patent. Patented July 7, 1914.

Application filed April 22, 1911. Serial No. 622,693.

To all whom it may concern:

Be it known that I, HERMAN H. DEUTSCHER, a citizen of the United States, residing at Carrollton, in the county of Carroll and State of Missouri, have invented certain new and useful Improvements in Farm-Gates, of which the following is a specification.

My invention relates to improvements in farm gates.

The object of my invention is to provide a simple, efficient and durable farm gate, which may be automatically opened and closed by a wagon, sled, or other vehicle moving past the gate in either direction.

The novel features of my invention are hereinafter fully described and claimed.

In the accompanying drawings which illustrate one form of my invention, Figure 1 is an elevation showing the gate in the open position. Fig. 2 is a plan view of the gate, shown in solid lines in the closed position and in dotted lines in the open position. Fig. 3 is an elevation showing the gate in the closed position. Fig. 4 is a cross section, enlarged, on the line *a*—*b* of Fig. 3, the solid lines showing the neutral position of the lever which operates the latch, and the dotted lines showing said lever in the position assumed by it after the latch has been opened in the opening operation of the gate. Fig. 5 is a cross section on the dotted line *c*—*d* of Fig. 1. Fig. 6 is an enlarged elevation of one of the crank shafts and parts connected therewith.

Similar reference characters designate similar parts.

1 designates a gate pivoted to a gate post 2 by hinges 3. Pivoted to the gate by a horizontal pin 4 is a latch 5 adapted to lock with a catch 6 on a post 7, when the gate is closed, as shown in Fig. 2. The latch 5 is also adapted to lock with a catch 8 on a post 9, when the gate is open, as shown in Fig. 1. A coil spring 10 is secured to the gate at one end, and at the other end is secured to the latch 5, at the right of the pin 4, as viewed in Fig. 1.

50 Secured to the gate near its bottom is a bracket 11 to which is pivoted on a vertical axis a lever 12, which extends past the post 2. To the forward end of the lever 12 is secured a flexible device, such as a chain 13 secured to one end of a coil spring 14, the other end of which is secured to the latch 5

at the right of the pin 4, as viewed in Fig. 1. The chain 13 extends between two rollers 15 and 16 respectively pivoted on parallel horizontal pivot pins 17 mounted in brackets 18 secured to the gate 1. The relations between the springs 10 and 14 are such that, when the gate is closed, the spring 10 will engage the latch 5 with the catch 6. The spring 14 must have sufficient strength to 60 overcome the spring 10 when the lever 12 is swung to open the latch. The rear end of the lever 12 has secured to it one set of ends of two rods 19 and 20 the other ends of which have longitudinally adjustable heads 70 21 and 22, each having a longitudinal slot 23.

At opposite sides of the gate 1 are posts 24 and 25 to which are respectively secured boxes 26 and 27 having mounted therein respectively rock shafts 28 and 29 having at 75 one set of ends respectively crank arms 30 and 31.

The crank arms 30 and 31 are provided respectively with two horizontal rollers 32 and 33. The crank arms 30 and 31 have 80 secured to them respectively below the rollers 32 and 33, two horizontal rods 34 and 35. The last named rods and the rollers 32 and 33 are adapted to be struck by a vehicle wheel, when in the positions shown in Fig. 85 3, and the vehicle is moving toward the gate 1, so as to rock the rock shafts 28 and 29 for the purpose of swinging the lever 12 to open the gate.

The rock shaft 28 is provided with an upwardly extending arm 36 having its upper end disposed horizontally and pivotally mounted in the slot 23 of the head 21. The rock shaft 29 is provided with a downwardly extending arm 37 having at its lower end a 95 horizontal portion pivotally mounted in the slot 23 of the head 22.

Two coil springs 38 and 39 are respectively secured at one set of ends to the posts 24 and 25, the other set of ends being respectively secured to the crank arms 30 and 31. The springs 38 and 39 serve to bring the crank arms 30 and 31 to the inclined positions shown in Figs. 1 and 3 after said arms have been swung to horizontal positions by the wheels of a passing vehicle.

Preferably the heads 21 and 22 are provided with screw threaded connection with the rods 19 and 20 so that they may be longitudinally adjusted on said rods.

When it is desired to open the gate 1 and the vehicle is moving to the left as viewed

in the drawings, the vehicle wheel will strike either the roller 33 or rod 35, depending upon the diameter of the wheel, and the crank arm 31 will be swung past the post 5 25 and to the horizontal position shown in dotted lines in Fig. 1, thus rocking the shaft 29 so as to swing the lever 12 to the positions shown in dotted lines in Fig. 4, thereby opening latch 5 by means of the chain 13, 10 which is pulled against the roller 15, and the coil spring 14, which as the lever 12 is swung, overcomes spring 10 and pulls the latch 5 against the horizontal pin 40 secured in the gate 1. The lever 12 will then 15 cause the gate to swing to the open position, the spring 14 now serving as a yielding means for swinging the gate. When the gate strikes post 9 the latch 5 will lock with the catch 8, thus holding the gate open. 20 After the vehicle wheel, not shown, has passed off from the roller 33 the spring 39 will swing the crank arm to the inclined position shown in solid lines in Fig. 1. After the vehicle has passed through the gate 25 way the vehicle wheel will strike roller 32, which with the crank arm 30 will have been moved to the position shown in Fig. 1, and will swing the roller 32 and crank arm 30 to the horizontal position at the other side 30 of the post 24, thereby rocking the rock shaft 28 so as to swing the lever 12 in a direction opposite to the direction in which it was swung when the gate was opened. The lever 12 will thus be swung past the neutral 35 position between the rollers 15 and 16 and the chain 13 will be drawn against the roller 16, thus pulling down the latch 5 to the open position by means of the spring 14, after which the lever 12 will cause the 40 gate to swing to the closed position shown in Fig. 4. When the wheel has passed off from the roller 32, the spring 38 will swing the crank arm 30 to the position shown in Fig. 3. All the parts will then be as shown 45 in Fig. 3.

The slots 23 in the heads 21 and 22 per-

mit the springs 10 and 14 and the chain 13 to swing the lever 12 to the neutral position, when the gate has been opened or closed.

A vehicle passing to the right, as viewed in the drawings, will operate the mechanism in a manner similar to that just described. It will thus be seen that a vehicle moving in either direction will automatically open and close the gate, if the vehicle is guided so as to have one of its wheels contact with the crank arm rollers.

Various modifications of my invention may be made, within the scope of the appended claims, without departing from the spirit of my invention.

Having thus described my invention, what I claim and desire to secure by Letters Patent, is:—

1. The combination with a swinging gate, of a rock shaft having a crank arm provided with two horizontal devices disposed at different distances from the axis of the rock shaft and adapted to be struck by a vehicle wheel so as to rock the rock shaft, and means for swinging the gate when the rock shaft is rocked.

2. The combination with a swinging gate, of a rock shaft having a crank arm provided with two horizontal devices disposed at different distances from the axis of the rock shaft and adapted to be struck by a vehicle wheel so as to rock the rock shaft, a post to which the rock shaft is pivoted, a spring connected to the crank arm and to the post for moving the crank arm from a horizontal to an inclined position, and means for swinging the gate when the rock shaft is rocked.

In testimony whereof I have signed my name to this specification in the presence of two subscribing witnesses.

HERMAN H. DEUTSCHER.
